UNITED STATES PATENT OFFICE

LEFFMAN H. LEE, OF PITTSBURGH, PENNSYLVANIA

INSULATOR

Application filed August 11, 1928. Serial No. 298,942.

This invention relates to electric insulators, such as are used for supporting electric conductors.

There have been, in general, several methods of mounting porcelain or glass insulators on poles, walls, and on various racks for their support. Since the electrical conductor which is supported by the insulator must not come into electrical communication with the object to which the insulator is attached, it has been found difficult to firmly mount either high or low tension insulators.

Due to the brittle nature of porcelain or glass it has been found impractical to use a threaded male extension integral with and composed of the material of said insulator for the aforesaid purpose of mounting the same. The result is that, heretofore, insulators, particularly those of the class illustrated in the accompanying drawings, have been cored out for the fixation of a threaded stem therein. In certain instances the interiors of these cored out openings have had threads impressed on their walls to receive a male portion which serves as the direct mounting means. But, to perfect such a manner of attachment, the cored out portion or hole has to be relatively large to allow the threads therein to be of a size to give sufficient strength. Furthermore, the male portion on which the insulator is screwed must have an outer layer or bushing of soft metal to permit the insulator threads to screw readily on the male portion. That is, the porcelain must contact a soft material or it will stick and cause the rupture of the insulator. This has proven a rather impractical and expensive means of mounting insulators.

Another common method of adapting insulators for mounting has been to center a screw or bolt shank in a cored out region of the insulator, and then, pour sulphur or lead therearound to serve as a binder and fix the so called male member in the insulator. It has been found that the torque necessary to mount the screw or bolt of this assembled insulator and screw is brought to bear on the porcelain portion of the insulator, and this

torque often causes breakage of the insulator before it is suitably mounted.

A further method of mounting insulators has been to cement or screw an internally threaded metal bushing into an insulator proper, to permit the insulator to be fixed to any suitable male shank. In all of the methods outlined there are, necessarily, several pieces carried in stock, and there is considerable work necessary in the field for the assembly of the insulator parts or pieces, and for the installation of each insulator. When a screw is permanently fixed in an insulator and screwed into an expandable wall plug, the rain and moisture attack the stem of the screw at the plane of jointure between the wall and the inner surface of the insulator.

The object of the invention is to provide an insulator with a metal core having an internally threaded portion extending from the face of the insulator to afford under certain conditions of installation a more rigid support for electric conductors.

In the accompanying drawings Figure I is a view of the insulator, shown partly in vertical section, illustrating a metal core secured in the insulator in accordance with my invention; Figure II is a view of an insulator in which a core of modified structure (an integrally cast core) is secured; and Figure III is a sectional view through a concrete wall, illustrating the manner in which the insulator of my invention proves advantageous in use.

The reference numeral 1 designates the insulator generally, and 2 represents a cored out portion or hole which opens into the base of the insulator. In Figure I there is shown a metal bushing 3 which is internally threaded at 4. It will be noticed that this bushing has a shoulder or irregular portion 5 which conforms in size and shape with the bottom of the recess 2. This similarity in conformation between the bottom of the recess and the inner end of the bushing aids in the casting operation, which is as follows:

The insulator is placed with the opening or recess facing upwardly, and the bushing 3 is dropped therein. Due to the aforesaid conformation of the bushing with re-

spect to the recess 2, the said bushing aligns and centers itself in the recess. Molten lead, sulphur, or other suitable material is then cast into the space between the bushing and the wall of the recess 2. The shoulder 5 serves to prevent the withdrawal of the bushing from the lead. In order that the resulting lead jacket or sleeve 6 may be neither rotated nor withdrawn, the inner wall of opening 2 has one or more indentations 7. When the said lead or other suitable binder is cast into the opening 2 and around the bushing 3, it fills the indentations 7, as shown.

Figure II shows an insulator in which a suitable metal has been cast to form the entire insulator-mounting core. The shoulder or extension 9 may be formed in the casting operation with the aid of a simple washer like mould, such as that illustrated by the dotted lines 10. This metal core 11 is solid after the pouring, but, obviously, upon drilling and tapping the core 11, as shown, the insulator is in condition for use.

Figure III is a sectional view, and shows a hole 12 drilled into a cement wall 13, and a bolt 14 fixed therein by expanding the ductile collar 15. This method of fixing bolts in a hole is well known, and it will not be necessary to describe it in detail. It should be noted that, heretofore, bolts of this type have always extended beyond the plane or surface of the wall in which they were positioned. This is an undesirable feature, since it often happens that the insulators are removed for a change in wiring or construction, and the bolts must remain fixed in the wall or be removed with great labor and expense. If the bolt end 14a is flush with the wall, it may be left therein, and the hole 12 may be plugged with a finishing material which does not mar the wall face. The primary advantage of the shoulders or extensions, such as the extension 9, is remarkable. The said extension permits the insulator to be mounted on a totally countersunk bolt shank. The extension is further advantageous in keeping moisture out of the hole 12 and away from the bolt 14. As the outer diameter of the extension is approximately equal to the inner diameter of the hole 12, it may be seen that the bolt 14 is held rigidly at both ends, and the external strain due the supported wire is distributed along the shank of the bolt instead of being concentrated on the member 15. It will be perceived that such distribution of stresses along the bolt would not exist if it were not for an extension, such as the extension 9, projecting into the hole 12. This structure results in a much firmer and stronger mounting than has been had in the past. It is found that the strength of this arrangement is so great that under a transverse pull (such as that exerted by a suspended electrical conductor) the porce-

lain will rupture before the bolts may be withdrawn.

The device is particularly advantageous for use in tile faced, or stucco covered walls; that is, it may be screwed on a toggle bolt 70 passing through the walls in the customary manner. The insulator screws up tight against the veneered wall surface and tends to hold the same against the wall rather than tending to pull the veneer away from the 75 wall.

It should be said that the insulators of the present invention are so simplified that they may be mounted by a simple screwing-on operation, and constitute in themselves complete articles of manufacture. On the contrary the practice of cementing threaded metal bushings or utilizing expansion sleeves in insulators has required the stocking and handling of both insulators and bushings 80 and/or expansions sleeves. The invention disclosed herein is not limited to relatively small and simple insulators of the type described, but it may be embodied in most types of high and low tension insulators. In claiming the invention, I have referred to the wall, 90 in which the insulator-securing bolt is fixed, as an insulator support. This is done for the reason that the invention is applicable to a support other than a wall; that is to say, I contemplate the use of my invention in mounting insulators on telephone poles, metal insulator brackets, racks, and the like.

What I claim is:

1. In combination with an insulator support, which support is provided with a hole and includes a threaded shank fixed to said support concentrically with and inwardly from the mouth of said hole; an insulator comprising a porcelain body having a metal core secured therein, which metal core is internally threaded and extends from the face of said insulator body to nest within the mouth of said hole and receive said threaded shank. 100

2. The combination of the next preceding claim, in which the metal core in addition to having the above defined structural characteristics comprises a bushing which is first machined and then secured with cast material in the insulator body. 110

In witness whereof, I hereunto set my hand.

LEFFMAN H. LEE.
